HEAT-SEALED VALVE BAG

Carl Henry Hartman, New Rochelle, N. Y., assignor to St. Regis Paper Company, New York, N. Y., a corporation of New York

Application August 7, 1944, Serial No. 548,393

4 Claims. (Cl. 229—62.5)

1

This invention relates to sealing bags so as to make them substantially water- and gastight, or to resist chemical, solvent, or other deleterious action of the contents. More particularly, it relates to sealing bags composed of one or more plies of paper and at least a partial lining of thermoplastic material. The invention is especially applicable to bags closed by a sewn seam, and may be used readily with valve bags.

In sewed end bags, there has been some difficulty encountered in completely avoiding leaks through the needle holes of the seam, and there is always danger of leakage through improperly closed valves of valve bags. It is the primary object of this invention to eliminate or minimize these difficulties. Other objects and features of the invention will appear as the description proceeds.

In the accompanying drawings forming a part of this specification—

Fig. 1 is a side elevation of a valve bag end to which the invention has been applied.

Fig. 2 is a section on the line 2—2 of Fig. 1 through the seam.

Fig. 3 is a section on the line 3—3 of Fig. 1, but showing the valve closed after the bag has been filled.

Fig. 4 is a view of a sheet adapted to form a sleeve in a valve, and Fig. 5 is a view of the sheet shown in Fig. 4 after portions thereof have been folded.

Fig. 6 is a side elevation of the bag end and of a heat-sealing device during the heat-sealing operation.

Fig. 7 is a section on the line 7—7 of Fig. 6, and Fig. 8 is a section on the line 8—8 of Fig. 6.

In the illustrated embodiment of the invention, it is applied to a gusseted valve bag.

As illustrated, there is a bag 10 with closure means 11 at one end, and provided with gussets 12, an inturned valve 13, and a valve sleeve 14. The bag is shown as having two layers 15 of paper and an inner layer 16 of thermoplastic material of a heat-sealing nature, preferably having appreciable elasticity. The material sold by the Goodrich Company under the trade name of Koroseal has been employed successfully.

A reinforcing tape 17 is applied over the top of the bag and is sewed to the bag, and may be adhered also. As shown in Fig. 2, the bag end is closed by a sewed seam 18 which passes through the bag walls and the reinforcing tape. The layer 16 is heat-sealed along the line of the closure. In the drawings, this sealing is indicated at 19, just below the line of stitches. The

2

sealing may extend along the line of stitches, but preferably should extend somewhat below also, to prevent the contents of the bag from reaching the needle holes, even if those holes are sealed.

5 Any suitable heat-sealing layer 16 may be employed, and the sealing may be done before, after, or simultaneously with the sewing, although sealing prior to sewing and prior to the application of the reinforcing tape has some advantages.

10 The Koroseal, mentioned above, may be pressed in liquid form onto a sheet of paper, so as to form a lining adhered to the paper, but is a material which may be reheated to a point where two layers thereof will coalesce without adhering to an ordinary paper surface, which fact is utilized in the manufacture of a sleeved valve bag.

15 In the form of valve shown in Fig. 3, the in-turned bag walls at 13 have their sealing layer 16 on their side toward the unturned bag walls.

20 but the edges of a sleeve 14 are inserted as at 22 between the inner edges of the valve and the unturned bag wall. The sleeve consists of an inner layer of paper 20 having a sealing layer 21 applied thereto. It will be seen that where the 25 edge of the sleeve is turned over at 22, the paper layer is next to the unturned wall and will not adhere thereto when heat is applied to coalesce layer 21 with layer 16 at the inner end of the valve, as indicated at 23 in Fig. 3.

30 Preferably, the outer end of the sleeve is folded in at 24 so layers 21 contact and may be heat-sealed at 25 after the bag has been filled. In forming the sleeve, a sheet may be used like that shown in Figs. 4 and 5. This sheet may be folded

35 along longitudinal line 26, and then inserted in the bag. The sheet is shown notched at its corners to provide an outer flap 27, and inner flap 28 and side flaps 29. Flaps 27 and 29 are first folded to bring their paper sides against the paper of the main sheet, while flap 28 is folded in the opposite direction, as shown in Fig. 5.

40 Then the sheet is folded about line 26, and the flap 28 inserted at 22 between the inner end of the valve and the bag walls, as previously described. The two flaps 29 are then at the upper edge of the sleeve, with their heat-sealing surfaces in contact. The bag at this stage may be 45 heat-sealed as indicated in Figs. 6 and 7.

Clamp members 30 may be operated by lugs 31 50 in any convenient manner to clamp the end of the bag between them. The clamps extend along the entire length of the seam, and are shaped to fit the bag end, providing for greater thickness at the gussets and reduced thickness along the top of the sleeve. A downwardly extending pro-

Section 32 is provided at the inner end of the sleeve and valve. Suitable conductors 33 are provided, properly insulated by members 34 from the clamps, and connected by means not shown to any suitable source of high frequency alternating current. By this means, sufficient heat is generated to seal together layers 16 along line 19, including the ends of the gussets, and where there is a sleeve valve, layer 21 is simultaneously sealed to layer 16 at the inner end of the valve and flaps 29 are sealed together along the top of the sleeve.

After the bag end has been sealed in this way, a seam as at 18 may be sewed along the end. Also, as previously indicated, the heat-sealing might take place after or simultaneously with the sewing. If preferred, the heat-sealing might be accomplished by applying heat by electrical or other means progressively across the bag end, and while for convenience the description has described the operation as taking place at the upper end of the bag, in practice it is immaterial what position the bag is in during the sealing operation. Omission of the valve, and/or the gussets, merely simplifies the sealing operation, which may be otherwise the same as described above.

After the bag has been filled, the outer end of the sleeve may be sealed by applying heat so as to make the contacting surfaces of flaps 27 coalesce, thereby completing the sealing of the bag and rendering it water- and airtight. If the bag is to be used for chemical or other material, the lining material is selected so as to retain the contents without injury to the bag.

Where the bag is closed by a sewed seam, it will be understood that the thread holds the bag walls together. If the inner surfaces coalesce below the seam, there is a tendency for the contents to force these surfaces apart. Where the heat-sealing material is elastic, it stretches enough to put the stress on the thread without forming a leakage opening. Less elasticity is required where the coalescence is directly along the line of stitches, especially where dependence is placed upon the material filling the needle holes.

For some purposes, the bag end could be sufficiently sealed by employing a reinforcing tape with heat-sealing material between the tape and the bag. The heat-sealing may be employed with bags which are left entirely open at the top until filled, or those which are only partly closed at the filling end before filling.

While other heating means might result in sealing the bags, the high frequency electric current is especially suitable for the purpose, since it makes possible a very rapid heating of the heat-sealing material without injury to paper outside thereof, and makes possible the application of the principle to a multiply bag and to the seam where the bag is gusset folded and so comprises many thicknesses of paper through which heat would be conducted very slowly from ordinary external application.

Where the thickness of the bag walls varies widely, suitable variations may be made in the insulation between the conductor and the bag wall, as indicated in Fig. 8, or variations may be made in the frequency or voltage of the current, so that the sealing will be accomplished in the same time at all points across the bag, or if preferred, the current may be applied for different intervals at different portions.

While for simplicity a complete lining of ther-

moplastic material has been described, it will be readily understood that the material need be thermoplastic only where it is to be sealed, and any suitable lining material may be employed at other points.

While one embodiment of the invention has been described in considerable detail, and some variations have been mentioned, it will be understood that other changes may be made within the scope of the appended claims.

What I claim is:

1. A multi-ply valve bag comprising a plurality of plies of paper, the inner ply of paper being lined with thermoplastic material, an end-closing sewed seam, a corner of the bag being turned in at one end of the seam to form a valve, a sleeve in the valve formed of a sheet of paper having its outer side covered with thermoplastic material, its inner end folded outward and the thermoplastic material thereon being heat-sealed to the bag lining material on the inner end of the valve, the longitudinal edges of the sheet being folded inward and their thermoplastic coatings being heat-sealed together along the line of said seam and the lining of said bag being heat-sealed the rest of the way along said seam, and the outer end of the sleeve being inturned whereby it may be heat-sealed after the bag has been filled.

2. A plural ply bag comprising an inner ply of pliable plastic material, a surrounding ply of paper, closure means for an end of the bag constructed and arranged with a valve at one corner, such valve having an inturned flap formed of said plies, and a valve sleeve therein which includes an inner ply of paper and an outer ply of pliable plastic material, the plastic material of the bag inner ply and of said sleeve being of a type such that contacting layers thereof will coalesce upon heating, surfaces of the plastic material along the inner edges of said flap being brought into contact and heat-sealed with respect to plastic surfaces along the inner end edges of said sleeve, while leaving a filling opening through the sleeve to the exterior of the bag, and the outer end edges of the sleeve being turned inwardly, thus positioning plastic surfaces thereon for contact and heat-sealing of the outer end of the sleeve after the bag is filled.

3. A plural ply paper bag having an initially flattened tubular body portion with end closure means constructed and arranged with a valve at one corner of the bag, the portions of the bag at the region of said end closure at least, having an inner ply of pliable plastic material, said valve having an inturned flap formed of said plies, and a valve sleeve therein also initially flattened within the bag, said sleeve including a ply of paper having at least on its inner end portions an outer ply of pliable plastic material, said plies of plastic material being of a type which will coalesce upon heating when in contact with each other but will not adhere effectively to paper, the inner end edges of said sleeve being folded over to form a cuff-like portion embracing the inner edges of said flap, and the surfaces of the plastic material along the inner edges of said flap being heat sealed with respect to plastic surfaces along the folded-over edges of said sleeve, while leaving a filling opening through the sleeve to the exterior of the bag, the valve flap and sleeve therein being left free to be generally flattened up against the inside of the closure when the bag is expanded and filled.

4. A plural ply paper bag having a sewn seam end closure means constructed and arranged with

a valve at one corner of the bag and the portions of the bag at the region of said end closure at least, having an inner ply of pliable plastic material, said valve having an inturned flap formed of said plies, and a valve sleeve therein which includes an inner ply of paper and an outer ply of pliable plastic material, said plies of plastic material being of a type which will coalesce upon heating when in contact with each other but will not adhere effectively to paper, the longitudinal edges of the plastic plies forming said sleeve being folded inwardly of the sleeve and coalesced along a line of juncture to form the sleeve as a tube open at both ends, the opposed inner ply surfaces of the bag being heat sealed together along said closure means, and the inner end edges of said sleeve being folded over to form a cuff-like portion embracing the inner edges of said flap, and the surfaces of the plastic material along the inner edges of said flap being heat sealed with respect to plastic surfaces along the folded-over edges of said sleeve, while leaving a filling open-

ing through the sleeve to the exterior of the bag, the valve flap and sleeve therein being left free to be generally flattened up against the inside of the closure when the bag is expanded and filled.
